UNITED STATES PATENT OFFICE.

WILLIAM J. EASTWOOD, OF PHILADELPHIA, PENNSYLVANIA.

DESIGN FOR A COMBINED SERVICE-FLAG AND PHOTOGRAPH-MOUNT.

52,867.

Specification for Design.

Patented Jan. 14, 1919.

Application filed October 23, 1918. Serial No. 259,438. Term of patent 3½ years.

To all whom it may concern:

Be it known that I, WILLIAM J. EASTWOOD, a citizen of the United States, residing at Philadelphia, in the county of Philadelphia and State of Pennsylvania, have invented a new, original, and ornamental Design for a Combined Service-Flag and Photograph-Mount, of which the following is a specification, reference being had to the accompanying drawing, forming part hereof.

The figure is a plan view of a combined service flag and photograph-mount showing my new design.

I claim:

The ornamental design for a combined service flag and photograph-mount as shown.

In testimony whereof, I have hereunto signed my name.

WILLIAM J. EASTWOOD.
